Inventor
Maurice Samuels

UNITED STATES PATENT OFFICE.

MAURICE V. SAMUELS, OF SAN FRANCISCO, CALIFORNIA.

MECHANICAL RECEPTACLE.

Application filed February 16, 1927. Serial No. 168,655.

My invention relates to a mechanical receptacle adapted to contain cigarettes or other smoker's materials suitable for pocket use and an extinguisher of fire for cigar or cigarette ashes, matches or the like and a compartment to retain such refuse.

Other objects will appear from the drawing and specifications which follow:

These objects I attain by employing a casing member and a container member which when telescoped together provide between them a compartment for receiving ashes and the like and a box or case for carrying cigarettes, cigars, matches, tobacco or the like.

The volume of the said compartment is increased by the extended telescopic movement of the members and decreased as they are collapsed and a side opening gives access to the said compartment through which the ashes are introduced.

Elastic means normally draw the two members together into collapsed position closing the said opening and thereby holding the contained refuse entrapped and excluding air and preventing combustion in the said compartment thus effectually extinguishing any remaining burning material.

In a preferable form of my invention a slide or other suitable form of closure means is employed to discharge the refuse contents from the said container and finger means are provided for manually overcoming the elastic means and extending the telescopic engagement of the members to expose the opening to the said container so that ashes may be introduced into said chamber and when the finger member is released the members are collapsed and the opening closed.

By referring to the accompanying drawing my invention will be made clear.

Fig. 1 is a side view of a preferred form of my device.

Fig. 2 is a vertical cross section on the line II—II of Fig. 3.

Fig. 3 is a horizontal section on the line III—III of Fig. 1.

Throughout the figures similar numerals refer to identical parts.

An external casing member is shown by the numeral 1, and an internal case or container member is shown at 2 adapted to telescope within the casing 1.

At 3 is a slide being one form of a removable bottom adapted to normally close the casing opening 11 and giving access to the space between the members to be opened to

discharge the contents as ashes, cigarette butts and the like that have been collected therein.

At 4 is an opening in the side of the casing member 1, through which ashes may be introduced into the compartment between the telescoping members when the member 2 is extended by overcoming the tension of the spring 13.

At 5 is a cover hinged at 14 adapted to normally close the member 2 and forming therewith a case or box for cigarettes or the like.

The spring 13 is fixed to the upper portion of the member 2 at 7 and to the lower portion of the member 1 at 15, and provides elastic means tending to draw the members 1 and 2 together and thereby force the bottom 12 towards the slide 3 to maintain a minimum volume at all times in the compartment 16, thus securing a minimum amount of air to suppress combustion therein and effectually extinguishing and holding retained in the said compartment 16, ashes, cigarette butts or other refuse.

In the side of the casing 1, I provide a slot 9, 9 through which extends the finger member 8 fixed with the member 2 and enabling the members 1 and 2 to be separated by overcoming the elastic means 13 when the finger forces the member 8 upwards.

When released the spring tension returns the members into collapsed engagement closing the opening 4 and quenching any refuse contained in the compartment 16.

In the embodiment of my invention here disclosed the spring 13 is completely enclosed in the tube 18 formed with the member 2 and a cooperating passageway formed in the member 1 as by the partition 19.

It will now be understood that other forms of my device than that here illustrated and described may be employed without departing from the spirit of my invention and I wish to be understood as claiming all such.

The operation is as follows:

The device is clasped in one hand and with the thumb, the member 8 is forced upward overcoming the tension of the spring 13 until the bottom 12 of the member 2 uncovers the opening 4 in the member 1 when ashes may be introduced through the opening 4 and fall into the container 16. The finger member is now released when the members telescopically collapse under the action of spring 13 and the bottom 12 closes on the ashes in

the said chamber 16 by the members being drawn together by the spring 13.

Further cigarettes are available from the box 17 by opening the top 5.

5. When the chamber 16 is to be emptied the slide 3 is withdrawn freely discharging the contents from 16.

Reference is herein made to my co-pending application Ser. No. 139,950 filed October 6, 10 1926 wherein is disclosed another species of my invention.

Reference is herein made to my co-pending application Ser. No. 294,646, filed July 23, 1928, wherein is claimed another form 15 of my mechanical receptacle not claimed herein.

I claim:

1. A case for cigarettes and the like in combination with a casing external to the 20 case and telescopically engaged therewith, a bottom for said casing, an opening in the side of the casing spaced from said bottom through which smokers' refuse may be introduced and trapped in the space between

the case and the casing when the case and 25 the casing are telescopically collapsed, a finger member fixed with the case and projecting through the casing adapted to displace the case clear of said opening.

2. A mechanical receptacle comprising a 30 casing and a case forming external and internal members respectively adapted to engage telescopically, elastic means adapted to collapse said members in said telescopic engagement, a lateral opening in the side of the external member adapted to be closed by the said telescopic movement of the other member, one end of said external member provided with movable closure means, a closed end on the internal member adjacent 40 said means providing a refuse chamber of variable volume during telescopic movement of said members, a movable top for the internal member, finger means constructed and adapted to telescopically extend the members 45 by overcoming said elastic means.

MAURICE V. SAMUELS.
